UNITED STATES PATENT OFFICE.

CLARENCE C. STIRLING, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

SNAP-SWITCH.

1,260,591.

Specification of Letters Patent. Patented Mar. 26, 1918.

Application filed June 22, 1917. Serial No. 176,302.

To all whom it may concern:

Be it known that I, CLARENCE C. STIRLING, a citizen of the United States, residing at Hartford, in the county of Hartford and State of Connecticut, have invented certain new and useful Improvements in Snap-Switches, of which the following is a specification.

This invention relates to snap-switches, the object of the invention being to provide an article of this character which is simple in construction and which can be rapidly moved to the on and the off positions in an effective and exact manner.

In the drawings accompanying and forming part of the present specification I have shown in detail a form of embodiment of the invention which I will set forth fully in the following description. I am not restricted to this particular disclosure; I may depart therefrom in several respects within the scope of the invention defined by the claims following said description.

Referring to said drawings:

Figure 1 is a horizontal section of the switch, the parts being shown in different positions by full and dotted lines respectively.

Fig. 2 is a vertical section of the same, the switching member being shown in the off and the on positions also by full and dotted lines respectively.

Fig. 3 is a vertical section of the device, the button, however, being partly in elevation and the section being on the line 3-3 of Fig. 1, looking in the direction of the arrows.

Fig. 4 is a transverse section on the line 4-4 of Fig. 3, looking in the direction of the arrow, and

Fig. 5 is a transverse section taken through the forward part of the switching member illustrated as being in the on position.

Like characters refer to like parts throughout the several views.

The device involves in its make-up a base such as that denoted in a general way by 2 and which may be made of any of the insulating materials now in ordinary use.

This base as shown is practically circular in form, and it supports a cap or case as 3 generally of sheet metal and practically of cylindrical form, its top being closed. The case is united with the base 2 in any desirable

manner, their diameters as shown being approximately equal.

The switch involves in its organization a suitable switching or circuit-controlling member such as that denoted in a general way by 4 and an actuator for said switching member, such as that denoted by 5 and both of which will be hereinafter more particularly described. The base 2 constitutes a suitable support for terminals as 6 generally of metal and which as shown are practically of L-form. The horizontal branches of these terminals 6 are perforated to receive the screws 7 extending through openings in the base 2, and the lower threaded ends of which receive nuts as 8 by which wires or equivalent conductors are connected to the screws, and as a consequence to the circuit-controlling or switching member 4.

Said circuit-controlling member as shown involves in its make-up the blades as 9 of suitable conducting material. As a matter of fact these blades are usually formed from sheet-metal. They are connected as by screws 10 to the body portion 11 of suitable insulating material, of the switching member, and as a result partake of the movements of said body portion. The rear ends of the blades 9 are practically coincident with the back edge of the body portion 11, but their forward ends extend beyond the front ends of said body portion for a reason that will hereinafter appear.

The switching member 4 is pivoted as shown between the terminals 6, and for this purpose screws as 12 may be utilized, the screws extending through the blades and being threaded into the insulating body portion 11, the screws obviously presenting journals to provide for the rocking or oscillation of the knife-blade switching member 4.

Separated from the terminals 6 are contacts as 13, the contacts as shown each consisting of a pair of L-shaped members as 14, the bases of which are superimposed and the upright portions of which, however, are spaced a distance sufficient to receive the blades 9 when the switching member 4 is in the on or circuit-closing position as indicated best in Fig. 5. The bases of the two pairs of L-shaped members 14 are perforated to receive the screws 15, the shanks of which extend through openings in the base 2 and the threaded ends of which are furnished

with nuts 16. As shown these screws 15 are connected by a wire 17 coiled about the same and held thereto by the nuts 16. This is merely illustrative. When the blades 9 5 of the switching-member 10 are from out of the vertical or upright portions of the contact 13 as shown for example by full lines in Fig. 2, it will be clear that the switching member is in the off position. To limit the 10 swing of the circuit-controlling or switching member, it may be provided upon its blades with screws 10 constituting suitable stops and which when in the extreme positions as shown for instance in full and dotted lines 15 in Fig. 2, will abut against the terminals 6 to arrest the switching member.

The actuator or operating means for the switching member involves in the organization illustrated, a spindle as 19 extending 20 through the bushing 20, the base 2 having a hole or perforation to comparatively snugly receive the bushing. The bushing is furnished at its lower end with an annular flange to engage the under side of the 25 base 2. The spindle 19 extends freely through the bushing to permit its easily being turned, and it may be provided at its lower end with a nut 21 to engage the flanged part of the bushing, and prevent 30 accidental upward displacement of the bushing. The spindle in addition is furnished with a stop collar as 22 fastened conveniently thereto as by a screw or otherwise, and which engages the upper edge of the 35 bushing 20 which as will be seen extends above the upper surface of the supporting base 2, to prevent displacement downwardly of the spindle 19.

The insulating body 11 of the switching 40 member 4 has an opening 23, the center of axis of which in the present case is intersected by the axis of motion or center of oscillation of the switching member 4. This opening or hole 23 is of sufficient diameter 45 to quite freely receive the spindle 19, and the wall of the opening will not come in contact with the spindle when the switching member is in the on and the off positions respectively. Said wall as shown consists of 50 two inwardly tapering surfaces which converge on a plane passing through the center of the insulating body or core 11.

The spindle 19 extends through a hole or opening in the top of the casing or shell 3 55 and receives a knob or operating member as 24 which can be secured to the spindle in any convenient manner as by a screw. The periphery of the operating member or knob 24 is roughened to facilitate its being turned. 60 The longitudinal axis of the spindle 19 in the present case extends through the axis of oscillation of the switching member 4.

I might note at this time that although as 65 described the switching member 4 has an oscillation or rocking motion, the spindle,

however, rotates but step-by-step, being adapted on each step in each direction, through suitable means, as by the spring 25, to impart the necessary snap movement to the switching member to cause the same to 70 move between on and off positions respectively. This spring encircles the spindle 19 between the switching member 4 and the knob or operating portion 24. The upper terminal coil of the spring is shown having 75 the extension 26 projected into an opening in the hub of the knob to thus connect the two parts. The lower terminal coil of the spring has a prolongation 27 terminating in a loop 28 overlying the insulating body 11. 80 The lower terminal coil 27, it will be understood, has no direct connection with the insulating body. It is adapted as a matter of fact to revolve around said body for a reason that will hereinafter appear. As 85 may be inferred the lower portion of the spring is free, the upper, however, being connected with the spindle. In Fig. 3 the switching member is shown in the off position and in similar relation by full lines in 90 Fig. 2, the lower portion 27 of the spring 25 bearing upon the insulating body or core 11 to the rear of its center of oscillation to maintain the said condition, the stops 18 being against the terminals 6. It will be 95 assumed that it is desired to move the switching member to the off position. In this case the spindle 19 will be turned through the action of the knob or operating portion 24, thus carrying the spring around 100 with the knob and necessarily with the spindle, causing the prolongation or projection 27 to traverse or sweep across the upper surface of the core or body portion 11 and naturally compressing the spring 24. As soon 105 as this projection has crossed the center of oscillation of the switching member, the spring can react or expand, and as it does so it will act against the core or body portion 11 to thus snap the switching member to 110 the on position or in the construction shown to move the blades 11 into the space between the upright portions of the contact 13, thus closing the circuit or moving the switching member to the on position. Obviously to 115 move the switching member to the off position, the operation to which I have alluded will be precisely reversed. It will be clear that the switching member can be moved irrespective of the direction of turning of 120 the spindle 19, the latter as illustrated being capable of rotary movement in either direction.

It is quite desirable that arcs which possibly might be created at the breaking end 125 of the circuit, be rapidly discharged therefrom, and I provide a means by which this condition is possible and will now describe the same as shown. Between the blades 9 and in front of the body 11, I dispose the 130

vane 29. This vane is of insulating material such as mica or isinglass. It abuts practically at its rear against the front of the core or body 11, its forward end, however, 5 being in advance of the blades 9. It is virtually composed of two duplicate integral portions which converge upwardly. The front of the sides of this vane 29 are cut away or slotted as at 30 to be free of the 10 forward or front ends of the blades 9, and thus provide airways down which air may rush as the switching member is moved to circuit opening position so as to forcibly blow or direct any arcs sidewise or at right 15 angles to the direction or path of the arcs. The vane or fan 29 extends between the 20 blades 9, and the side walls of the slots are adapted to practically traverse the inner faces of the contacts 13 as the switching member is moved between its on and off positions. The movement of the angular vane or fan between the on and the off positions as will be clear, causes a rush of air across 25 the spark gap or gaps just at the moment of breaking, thereby blowing out the arcs. As the vane moves very quickly, it functions as a fan.

What I claim is:

1. An electric snap switch comprising an 30 oscillatory switching member, a turnable spindle in correlation with the switching member, the axes of motion of the two approximately intersecting, and a coiled spring encircling the spindle and connected therewith, the spring having a free portion 35 directly engaging the switching member to sweep across the center of motion thereof on the turning of the spindle for successively moving the switching member to on 40 and off positions.

2. An electric snap switch comprising an oscillatory switching member, a turnable spindle in correlation with the switching member, and a spring connected with the 45 spindle to turn therewith, the spring having a free portion directly engaging the switching member, and to sweep across the center of motion thereof on the turning of the spindle for successively moving the switching 50 member to on and off positions.

3. An electric snap switch comprising an oscillatory switching member and a spring to directly engage the switching member at

all times, and means for turning the spring to cause the same to sweep across the center of motion of the switching member to successively moving the latter to on and off positions.

4. An electric snap switch comprising an oscillatory switching member, a spiral 60 spring having an extension at one end directly engaging the switching member at all times, and means for turning the spring to cause the same to sweep across the center of motion of the switching member and successively move the same to on and off positions.

5. An electric snap switch comprising an oscillatory switching member, a turnable spindle in correlation with the switching 70 member, the axes of motion of the two approximately intersecting, and a coiled spring encircling the spindle and connected at one end therewith, the other end of the spring having an extension directly engaging the switching member and to sweep across the center of motion thereof on the turning of the spindle for successively moving the switching member to on and off positions.

6. An electric snap switch comprising an oscillatory switching member, a spiral spring having an elongated yielding extension at one end directly engaging the switching member, and means for effecting the action of the spring to cause the extension thereof to sweep across the center of motion of the switching member to successively snap the same to on and off positions.

7. An electric snap switch comprising an 90 oscillatory switching member, a spiral spring having a free straight end directly engaging the switching member, and means for turning said spring around the longitudinal axis of its coiled portion to cause said 95 straight end to sweep across the center of motion of the switching member for successively moving the same to on and off positions.

In testimony whereof I affix my signature 100 in the presence of two witnesses.

CLARENCE C. STIRLING.
